LEATHER CLEANING COMPOSITION

Wallace J. Yates, Martinez, Calif., assignor to
 Shell Development Company, San Francisco,
 Calif., a corporation of Delaware

No Drawing. Application November 5, 1934,
 Serial No. 751,577

2 Claims. (Cl. 87—5)

This invention relates in general to leather cleansers and more particularly to a cleaner for finished leather goods such as suede leather jackets.

5 The cleaning of soiled finished leather particularly leather jackets has in the past been a problem with the dry cleaning industry owing to the wide variety of spots and types of dirt with which the leather jackets became soiled. Such 10 substances as varnish, paint, blood, grease, milk et cetera, often saturate the leather in places rendering their removal most difficult, even when prespotting with a strong solvent which often removes also the dye in the leather. A common 15 practice is to submit the leather to the usual dry cleaning treatment with a suitable hydrocarbon solvent, frequently with a final operation of scraping, e. g. with sandpaper, to remove spots not taken out in dry cleaning.

In the past, cleaned leather jackets often 20 emerged from the cleaning process with blue, lavender, green or gray stains in them which cannot be removed with the usual solvents.

It is an object of this invention to provide a 25 leather cleanser which will readily remove or soften spots of foreign substances on the leather. A further object of the invention is to provide a leather cleanser which will not remove the dye from the leather in appreciable quantities. A further object is to provide a cleanser which will 30 not adversely affect cleaning solvent systems, into which some of the cleanser is certain to pass.

Another object of this invention is to provide 35 a leather cleanser which will not produce colored stains in the dry cleaned article. The foregoing objects and other which will be apparent, I prefer to accomplish with a product obtained by mixing a given amount of alkali with an excess of iron free oleic acid to form an oleate 40 with some free oleic acid present. The resulting soap is then dissolved in a hydrocarbon solvent having a relatively high percentage of aromatics, or a chlorinated solvent such as carbon tetrachloride.

45 A small amount of pine oil, or pine oil derivative such as dipentene, or a low boiling alcohol may be added to the mixture as an additional solvent.

50 The novel features that I consider characteristic of my invention are set forth with particularity in the appended claims. The invention, however, together with advantages thereof will be best understood from the following description of a specific example of my cleaner.

8.3 gallons of a 48% solution of U. S. P. potassium hydroxide are mixed with 57 gallons of iron free oleic acid to form a soap containing an excess of oleic acid. The soap is then added to 875 gallons of hydrocarbon solvent having the following characteristics:

Aromatic content plus or minus 60%
 Aniline pt. max. 15° C.

Distillation range 135 to 195° C.
 Flash point. (Tagliaube open cup) plus or minus 10° F.

70 gallons of dipentene and 12.5 gallons of secondary butyl alcohol are added to complete the composition. The excess amount of oleic acid, 15 dipentene, and alcohol, in addition to adding desirable solvent qualities, aid in dissolving the potassium oleate in the solvent.

From the standpoint of performance complete solubility of the soap in the solvent is not 20 essential, although where the product is to be stored mutual solubility of all the ingredients is desirable in order to prevent stratification, and corrosion of metal containers.

The purity of the oleic acid is of importance, 25 for I have found that the colored streaks appearing in dry cleaned leather goods are the result of reaction between chemicals remaining in the leather from the tanning process with small amounts of iron salts so that as small a 30 percentage as .002% (as Fe_2O_3) in the oleic acid 35 will produce a discoloration of the cleaned leather. Commercial shipments of "white" oleic acid have contained iron in amounts varying from 0.02-0.002% (as Fe_2O_3).

As a preliminary step in the manufacture of 35 my composition I remove the traces of iron soap from the oleic acid by treatment with a small amount of aqueous tannic acid, after which the aqueous liquor containing the iron as tannate 40 is drawn off and the purified oleic acid is water washed to remove the remaining tannic acid. By this means I have been able to reduce the iron content of the oleic acid to such an extent 45 that my soap contains less than .001% iron, although it will of course be realized that it is preferable to remove all traces of iron.

While it is preferable to use a solvent with as high an aromatic content as possible, any percentage of aromatics over 20% will serve. While 50 I prefer to use a hydrocarbon fraction having a high flash point, at the same time it is desirable to have a solvent which has an end point sufficiently low to permit ready evaporation of the cleanser. It is obvious that other suitable 55

solvents might have a boiling range different from that given in the example.

- The preferred method of using the cleanser is as follows: the leather goods are run for a few minutes in a dry cleaning washer, containing one of the usual cleaning solvents in order to remove loose dirt. The solvent is then wrung out of the leather goods which are next soaked up to an hour or more in my cleanser. After wringing out the cleanser the leather goods are dry cleaned in the usual manner. Besides being used as a soaking solution my cleanser can be used as a prespotter or added to the cleaning solvent.
- 15 My leather cleanser has been found to remove oil and grease spots and to loosen the gums and resins of many paints and varnishes as well as to remove blood, and water soluble spots produced by sugar solutions, jam, etc. My leather cleanser has been found more effective than when using the ingredients separately. For example, while aqueous solutions can be used for the removal of blood, they have the undesirable effect on drying of rendering the leather stiff so that a supplemental treatment is necessary to restore the suppleness to the leather. On the other hand, by the use of petroleum products alone, blood spots in leather are fixed more permanently. Contrasted with this, my leather cleanser effectively loosens the blood spots so that they are readily removed in the usual dry cleaning or, in case of resistant paint spots, etc., by brushing, after application of the cleanser and prior to rinsing in solvent.
- 30 Another advantage of my cleanser as before stated is that the formation of colored patches in the leather is prevented.
- 35 Although I have described certain specific

embodiments of my invention, I am aware that modifications thereof are possible. While I have used my cleanser on leather goods, it should be understood that it may also be used as a cleanser for other materials. The invention therefore is not to be restricted, except insofar as is necessary by the prior art and the appended claims.

I claim as my invention:

1. The process of preparing an improved leather cleaning composition comprising subjecting a substantially pure commercial oleic acid, which contains combined iron in a concentration sufficient to cause the discoloration of leather cleaned with a cleanser containing a dry-cleaning soap of said acid, to the chemical action of tannic acid under conditions to form iron tannate and to reduce the concentration of iron in said oleic acid to less than .001%, separating the treated oleic acid containing less than .001% iron from the iron tannate, saponifying the separated oleic acid to form a dry-cleaning soap, and mixing said soap with a dry-cleaning solvent.

2. The process of preparing an improved leather cleaning composition comprising subjecting a substantially pure commercial oleic acid containing combined iron in a concentration of more than .001% to the chemical action of tannic acid under conditions to form iron tannate and to reduce the concentration of iron in said oleic acid to less than .001%, separating the treated oleic acid containing less than .001% iron from the iron tannate, saponifying the separated oleic acid to form a dry-cleaning soap, and mixing said soap with a dry cleaning solvent.

WALLACE J. YATES.
